PUNCH, DIE, AND PRESS ASSEMBLY

Edward S. Cornell, Jr., Larchmont, N. Y.

Application January 24, 1939, Serial No. 252,514

8 Claims. (Cl. 113—44)

This invention relates to a novel assembly of punch, die, and press, arranged for coaction in carrying out a forming operation on material capable of plastic deformation.

The present invention is related in many respects to the subject matter of my co-pending application, Serial No. 60,171, filed January 22, 1936, and entitled Die holder. The disclosure of that application may be profitably considered in connection with the herein disclosure. There, the specific embodiment illustrated and described comprises punches, together with suitable coacting press and die arrangement, adapted to exert solely mechanical pressure, as contrasted with the preferred embodiment herein illustrated and described which comprises punches, together with suitable coacting press and die arrangement, adapted to exert both mechanical and hydraulic pressure in a manner considerably improved over that of the former embodiment.

In the present instance, a similar arrangement of wedge means is utilized in connection with a split die for tightly closing the sections of the die along the line of split and for retaining such sections of the die in tightly closed status during the pressure stroke of the punches operable within the die. However, a radically different punch arrangement, with press arrangement to suit, is employed.

Apparatus, pursuant to the present invention, is primarily adapted for the shaping of hollow bodies from a material capable of plastic deformation under combined pressure of punches and a hydraulic medium, within the confines of a die. The apparatus is designed to carry out the method broadly disclosed and claimed in my copending application Serial No. 63,853, filed February 14, 1936, entitled Method and means of producing wholly integral cold wrought T's and like fittings. The material particularly contemplated for fashioning by the apparatus is metal predominantly of copper content, and, in many cases, is substantially pure copper, the metal being worked in its cold state. The hydraulic medium employed may be water, or other substantially non-compressible fluid, but is preferably a relatively light bodied lubricating oil. Hollow bodied articles most commonly produced by the apparatus are pipe fittings of various type, such as T, Y, and other multiple branched configurations.

A primary object of the invention is the provision of a punch, die, and press assembly,

adapted to produce hollow bodied articles with improved operating efficiency and economy.

An object is the provision of a punch, die, and press assembly arranged so as to coact in smooth, positive, and uniform manner, ensuring long life to the operating parts.

An object is the provision of a punch, die and press assembly adapted to carry out the method disclosed in the aforementioned copending application Serial No. 63,853, in a particularly effective manner.

In accomplishing the aforesaid objects, an outstanding feature of the invention is the provision for wedging cooperation between the punches and means associated with the bed of the press to effect pressure for the forming operation.

A further feature is the provision for maintaining the split die against any material flow at the location of split during exertion of the above specified pressure.

Further features and objects will be apparent hereinafter.

In the drawings, which illustrate a preferred embodiment of the invention:

Fig. 1 represents a vertical section taken along the line 1—1, Fig. 2;

Fig. 2 represents a vertical section taken along the line 2—2, Fig. 1;

Fig. 3 represents a vertical section similar to that of Fig. 1 but illustrating the ram in its lowered or pressure effecting, position; the view is slightly enlarged and has outer portions broken away;

Fig. 4 represents a vertical section similar to that of Fig. 2, but taken on the line 4—4, Fig. 3;

Fig. 5 represents a horizontal section taken on the line 5—5, Fig. 4;

Fig. 6 represents a vertical section taken on the line 6—6, Fig. 5;

Fig. 7 represents a vertical section taken on the line 7—7, Fig. 1, illustrating in detail how the die sections are interlocked; and

Fig. 8 represents a perspective view of a T pipe fitting produced by the apparatus illustrated in the foregoing figures.

Referring to the drawings: the press is indicated as having a bed 10 and a ram 11, see especially Figs. 3 and 4. Its general construction may be according to accepted engineering principles for producing the pressures required to successfully operate on the various materials capable of plastic deformation pursuant to the invention.

Formed on the bed 10 of the press, by means of

slideway elements 10-1 and 10-2, is a well 12 providing a slideway for the reception of a punch and die assembly, together with structure appurtenant thereto. The well 12 is formed, as hereinafter fully described, for cooperation with the punches in producing the pressures effective directly on the material within the die.

The punch and die assembly illustrated is adapted to work the raw material by a combination of mechanical pressure—exerted by the punches—and hydraulic pressure—exerted by a substantially non-compressible fluid medium. A variety of types of hollow bodied articles, and particularly those having angularly related branches, may be produced by apparatus constructed pursuant to the generic inventive concept here disclosed. The present specific embodiment of the apparatus is adapted to produce a T pipe fitting, as illustrated, per se, and indicated A, in Fig. 8. To this end, the punches, indicated at 13 and 14 may be formed with hollow tubular punch portions 13a and 14a, respectively, and head portions 13b and 14b, respectively. The material to be shaped may be a length of hollow tube having open ends, see 15.

The hollow tube of raw material 15 is preferably slipped onto a hollow tubular mandrel, as at 16, formed with an outer diameter of such dimension as to provide a close sliding fit with the inner walls of the hollow tube of material 15. The mandrel 16 is open-ended and has a port 17 provided through the tubular wall thereof adjacent its mid-portion. The hollow tubular punch portions 13a and 14a of the punches 13 and 14, respectively, are substantially of the same diameter and wall thickness as the tubular material 15, and, after the tubular material 15 has been positioned on the mandrel 16, are adapted to slide over the ends of the mandrel into abutting relationship with the ends of the tubular material.

The head portions 13b and 14b of the punches 13 and 14, respectively, are provided with fluid flow passages 18 and 19, respectively, opening at the upper part of the head portions 13b and 14b and leading downwardly through such head portions into communication with the hollows of the tubular punch portions 13a and 14a.

The punches 13 and 14, and the mandrel 16 are formed as independent elements adapted for association with the tubular material 15 in providing a unit extending within and without the confines of a split die 20.

The split die 20 may be formed in sections 20-1 and 20-2, cooperatively associated by means of dowel pins 21, 21 and dowel receiving recesses 22, 22, see particularly Fig. 7. The individual die sections may be formed in any suitable manner to cooperatively provide a die cavity suitable for the formation of the desired article, in the present case, the T pipe fitting A, Fig. 8. As illustrated, inset portions 20-1a and 20-1b, in their respective sections 20-1 and 20-2 of the split die 20, may be provided to form the lateral branch 23, see Figs. 1 and 2, of the die cavity, and inset portions 20-1c, 20-1c and 20-1d, 20-1d, in their respective sections 20-1 and 20-2 of the split die 20, may be provided to form entering passages for the punch portions 13a and 14a. A plug 20-3 serves to define the outer limit of the lateral branch 23, and is held in position by its circumferential collar portion 20-3a.

Each section 20-1 and 20-2 of split die 20 has portions, see 20-1e and 20-1f and 20-2e

and 20-2f, which extend outwardly at each side of the section adjacent the top thereof forming continuations of the contacting die faces, and providing guideways, see particularly Fig. 6, for the positioning of the heads 13b and 14b, respectively, of the punches. Such portions extend outwardly sufficiently far to overlap the openings of the fluid flow passages 18 and 19 of the punch heads 13b and 14b, respectively, when the punches are operatively disposed with respect to the die. Thus, the extending portions 20-1e and 20-2e, and the extending portions 20-1f and 20-2f, serve to seal the openings of fluid flow passages 18 and 19 of the punch heads against outward flow during the forming operation. Assuming the hollow of the mandrel and the hollows of the punches to have been filled with hydraulic medium in any suitable manner—as by manually pouring such hydraulic medium into the openings of fluid flow passages 18 and 19—before final positioning in split die 20, extensions 20-1e, 20-2e and 20-1f, 20-2f serve to entrap the hydraulic medium within the confines of the unit formed by the punch, mandrel, and raw material.

For maintaining the positioning of the punch, mandrel, and raw material unit with respect to the split die 20, a latch mechanism, indicated generally at 24, Figs. 1 and 6, may be employed.

The split die 20 is formed to fit between a bottom bridge element 25 and a top bridge element 26 of a die holder, the die holder being itself arranged to be received between the bed 10 and the ram 11 of the press for vertical reciprocation into and out of the well 12.

The bridge members 25 and 26 are configured to provide upwardly extending end walls 25a and 26b, respectively, which serve to provide a confining passage for the reception of the split die 20 and wedge members, hereinafter described.

The placement of the bridge members 25 and 26 relative to each other is determined by outer wedge blocks 27 and 28, such wedge blocks being slightly greater in height than the split die 20 to facilitate positioning of the latter in the die holder. The bridge members 25 and 26 are secured to each other, as by means of machine screws 29, 29 and 30, 30, Figs. 4 and 5. Passing through suitably placed and aligned apertures in the bridge members 25 and 26, and serving to position the bridge members relative to the ram 11, are stripper rods 31 and 32. These stripper rods are rigidly secured in the ram 11, as for instance as shown in my copending application Ser. No. 60,171, and extend through bores in the bridge members to project downwardly into the bores 33 and 34 provided in the bed 10 of the press. The bores in the lower bridge member 25 have their lower portions counterbored, as at 35 and 36, above and in alignment with the bores 33 and 34, for passage of the knobbed end portions 31a and 32a of stripper rods 31 and 32 into abutment against the closed upper ends thereof.

When the ram 11 forces the die holder down into the well 12, the stripper rods 31 and 32 are disposed as illustrated in Fig. 4, that is, depending freely within the bores 33 and 34. When the ram 11 raises, the stripper rods 31 and 32 are raised therewith until their knobbed head portions 31a and 32a engage the closed upper ends of bores 35 and 36, whereupon the entire die holder is raised from the well 12, see Figs. 1 and 2.

Disposed inwardly of the die holder next ad-

ja cent the outer wedge blocks 27 and 28, and defining passage for split die 28 into the holder, are inner wedge blocks 37 and 38.

The mounting for such inner wedge blocks 37 and 38 may be of the spring type, as disclosed in my copending application Serial No. 60,171, or, if desired, the resilient mounting may be dispensed with. Rods 39 and 40 extend upwardly from resilient or other desired type of anchor 10 age (not shown) through suitably provided bores in the bed 10 of the press and in the lower bridge member 25, see the bores 41 and 42, Fig. 3. Adjustably secured in the upper ends of the rods 39 and 40, respectively, as by screw thread en- 15 gagement, are wedge block carrying rods 43 and 44, the diameter of the greater part of their lengths, see 43a and 44a, being considerably reduced over the diameters of rods 39, 40. The upper ends of the wedge block carrying rods are 20 of enlarged diameter, as at 43b and 44b, terminating in formations, as at 43c and 44c, adapted for engagement by a wrench in the operations of securing and adjusting such rods relative to the lower rods 39 and 40.

25 The inner wedge blocks 37 and 38 are provided with preferably centrally located bores which extend throughout the heights thereof for receiving the reduced diameter portions 43a and 44a, respectively, of wedge block carrying rods 43 and 44. Such rods are threaded into the upper ends of lower rods 39 and 40 subsequent to the positioning of the wedge blocks thereon.

26 The upper bridge member 26 is provided with bores, see 45 and 46, Fig. 4, through which the upper portions of enlarged diameter, 43b and 44b, of carrying rods 43 and 44, extend.

It is preferred that the inner wedge blocks 37 and 38 be resiliently supported. Accordingly, 30 they may be provided with bores 47 and 48, and 49 and 50, respectively, extending upwardly from the bottom faces thereof to closed-end termination in the upper portions thereof. Positioned within such bores may be coil springs 51 and 52, 35 and 53 and 54, respectively. The coil springs are tensioned between the upper surface of lower bridge member 25 and the closed upper ends of the bores by which they are received.

When the ram 11 is in its raised position and 40 stripper rods 31 and 32 are supporting the die holder above the well 12 of the press, see Figs. 1 and 2, inner wedge blocks 37 and 38 rest freely on their spring mountings, and the upper ends of rods 39 and 40 are disposed within the bores 41 and 42, out of contact with the inner wedge blocks. In this position, the distance between the inner faces of the inner wedge blocks 37 and 38 is slightly greater than the width of the split die 28, thus affording free passage of the split die into the die holder.

As the ram 11 descends and forces the die holder into the well 12 of the bed 10 of the press, the die holder descends relative to the rods 39 and 40 and the wedge carrying rods 43 and 44, until the upper ends of rods 39 and 40 abut against the lower ends of inner wedge blocks 37 and 38, whereupon, further descent of the ram 11 forces the die holder, with its outer wedge blocks 27 and 28 and contained split die 28, downwardly relative to the inner wedge blocks 37 and 38. Thus, wedging action is effected against the two sections 28-1 and 28-2 of split die 28, which accomplishes extremely tight closure of the line of split between the two die sections during the forming operation of the

punches 13 and 14, and of the hydraulic medium, on the raw material 15, see Figs. 3 and 4.

The forming operation is accomplished by pressure exerted due to cooperation between the punches 13 and 14 with coordinating portions 5 of the well 12.

The slideway elements 10-1 and 10-2, which, together, define the well 12 on the bed 10 of the press, may be secured together by bolts, indicated 55, on which are strung spacers indicated 10 56. Recesses 57 and 58, vertically aligned with head portions 13b and 14b, respectively, of punches 13 and 14, are formed in the upper inner margins of the slideway elements 10-1 and 10-2, respectively. Inset into the recesses 57 15 and 58 are striker plates 59 and 60, respectively, such striker plates having their upper portions downwardly and inwardly beveled to provide guideways 59a and 60a for cooperation with the downwardly wedge shaped heads 13a and 14a 20 of the punches.

When the ram 11 descends and forces the die holder into the well 12, the punches 13 and 14 are wedged inwardly by reason of the cooperative relationship between the heads 13b and 14b 25 of the punches and the guideways 59a and 60a of the striker plates. Accordingly, the hollow tubular punch portions 13a and 14a of the punches squeeze the material of the tube 15, and, with the aid of pressure of the entrapped hydraulic medium, force portions of the material into the lateral branch recess 23 of the die, as is clearly illustrated in Fig. 3. It should be noted, that, while the punches are accomplishing their pressure operation, the sections 20-1 and 20-2 30 of the split die are being tightly forced together by the action of the inner wedge blocks 37 and 38, as hereinbefore explained.

Raising of the ram 11, following the pressure stroke thereof, lifts the die holder out of the well 40 12 by reason of the abutment of knobbed portions 31a and 32a of stripper rods 31 and 32 against the shouldered upper ends of counterbores 35 and 36, and, coincidentally, remove the rods 39 and 40 from their positions supporting 45 inner wedge blocks 37 and 38. Accordingly, inner wedge blocks 37 and 38 drop downwardly into their normal supported position as shown in Fig. 2. The split die 28 may then be removed 50 from the die holder for removal of the completely formed article.

For facilitating insertion of the split die 20 into, and withdrawal of the same from, the receiving passage formed in the die holder between the inner wedge blocks 37 and 38, a slideway 55 platform is formed at the top of slideway element 10-1 in horizontal alignment with the receiving passage of the die holder. Such platform is formed in part by a stationary top portion 10-2a of the slideway element 10-2, such stationary 60 portion forming substantially a right angle with an upstanding slideway wall portion 10-2b. The remaining portion of the platform is provided by a slide element 61 having a foot portion 61a slidably mounted on a slideway bed 10-2c 65 formed at the top of slideway element 10-2. A tongue 10-2d, and a parallel tongue 61b are formed on the upper surfaces of platform portions 10-2a and 61a, respectively. Grooves 62 and 63 are formed on the bottom surfaces of sections 20-1 and 20-2, respectively, of split die 28 for sliding fit over the tongues 10-2d and 61b, respectively, at such times as the split die 70 28 is withdrawn from the receiving passage of the die holder.

An arm 64, secured to the top of upstanding wall 10-2b and an arm 65 secured to the top of the upstanding wall portion of slide 61 have depending tongues 64a and 65a, respectively, 5 preferably vertically aligned with the tongues 10-2d and 61b, respectively, for sliding engagement with grooves 66 and 67 formed in the top surface of sections 20-1 and 20-2 of split die 20. Thus, split die 20 is firmly held in its position 10 on the platform.

For opening and closing the split die 20 to enable insertion and withdrawal of the unit made up of the punch, mandrel, and raw material, suitable mechanism such as the rack and pinion 15 arrangement illustrated in my copending application Serial No. 60,171, is operatively associated with slide 61. Operation of the provided mechanism effects travel of slide 61 away from slideway wall 10-2b, and, thus, by reason of the 20 engagement of tongues 10-2d and 61b with grooves 62 and 63, respectively, and tongues 64a and 65a, with grooves 66 and 67, respectively, effects corresponding travel of die section 20-2 away from die section 20-1. Operation of the 25 provided mechanism in the reverse manner effects reuniting of the die sections 20-1 and 20-2 subsequent to removal and replacement of the unit made up of the punch, mandrel, and raw material.

30 The specifically illustrated and described embodiment comprises two punches oppositely disposed from each other and guideways suitably formed in the well of the press for coordination therewith. It should be noted, however, that 35 one or several punches may be employed in substantially any mutually cooperative relationship and that guideways may be provided to suit, within the generic scope of the invention.

Whereas this invention has been described 40 with respect to a particular embodiment thereof, it is to be clearly understood that many changes may be made without departing from the generic scope of the invention as set forth herein and in the claims that follow.

45 I claim:

1. In combination with a press having a bed and a ram, a die holder disposed between said bed and said ram; a split die slidably mounted in said die holder; punch means operable within the 50 recesses of said split die and having wedge-shaped head means protruding from said split die; guideway means associated with said bed for cooperation with said wedge-shaped head means of the punch means, during the pressure stroke 55 of the ram, in the accomplishing of a forming operation within the recesses of said split die; movable wedge means associated with said split die; means anchored to said bed for moving said movable wedge means during the pressure stroke 60 of said ram, and for thereby tightly closing said split die, and for retracting said movable means during the return stroke of said ram.

2. In combination with a press having a bed and a ram, means associated with said bed and 65 forming a well thereon; a split die associated with said ram; means for retaining said split die tightly closed during the pressure stroke of said ram; said split die having a substantially rectilinear tubular recess and a branch recess 70 angularly related thereto; an open ended, substantially rectilinear, hollow, tubular mandrel adapted for the reception of a length of hollow tubular material in close sliding fit thereon, and, further, adapted for positioning within said substantially rectilinear recess of said split die;

75 punches having hollow tubular portions adapted for close sliding fit about the ends, respectively, of said mandrel, said punches having wedge-shaped head portions which protrude from said split die; fluid flow passages opening at the tops 5 of said head portions of the punches and extending into communication with the hollow tubular punch portions of the punches; a passage extending through the tubular wall of said mandrel toward the branch recess of said split die; means 10 for sealing the openings of said fluid flow passages during the pressure stroke of said ram; and guideways arranged in said well for cooperation with said wedge-shaped head portions of the punch means during the pressure stroke of 15 the ram in the accomplishing of a forming operation within the recesses of the said split die.

3. In combination with a press having a bed and a ram, a split die associated with said ram; means for retaining said split die tightly closed 20 during the pressure stroke of said ram; a hollow tubular mandrel, having a length of hollow tubular material slidably fitted about its mid-portion, positioned within a receiving recess of said split die; punch elements having hollow tubular punch 25 portions slidably fitted over respective ends of said mandrel with their punch ends abutting against the ends of said hollow tubular material, said punches having wedge-shaped head portions protruding from said split die and having fluid 30 flow passages opening at the extension of said wedge-shaped head portions and communicating with said hollow tubular punch portions; guideways associated with said bed for cooperation with said wedge-shaped head portions of the punches 35 during the pressure stroke of the ram in the accomplishing of a forming operation within the recesses of the said split die; and for closing the exterior opening of said fluid flow passages during the said forming operation.

4. In combination with a press having a bed and a ram, means associated with said bed and forming a well thereon; a die holder associated 40 with said ram; a split die slidably mounted in said die holder; movable wedge means mounted 45 in said die holder; means anchored exteriorly of said die holder and extending into operative relation with said movable wedges; punch means having punch portions operable within the recesses of said split die and having wedge-shaped 50 head portions protruding from said split die; and guideways arranged in said well for cooperation with said wedge-shaped head portions of the punch means, during the pressure stroke of the ram, in the accomplishing of a forming operation within the recesses of the said split die; said means anchored exteriorly of the die holder being effective, during the pressure stroke of the ram, to actuate said wedge means in forcing the sections of said split die tightly together along 55 the line of split.

5. In combination with a press having a bed and a ram, means associated with said bed and forming a well thereon; a die holder associated 65 with said ram; a split die slidably mounted in said die holder; movable wedge means resiliently mounted in said die holder; means anchored exteriorly of said die holder and extending into operative relation with said movable wedges; punch means having punch portions operable 70 within the recesses of said split die and having wedge-shaped head portions protruding from said split die; and guideways arranged in said well for cooperation with said wedge-shaped head portions of the punch means, during the pressure 75

stroke of the ram, in the accomplishing of a forming operation within the recesses of the said split die; said means anchored exteriorly of the die holder being effective, during the pressure stroke of the ram, to actuate said wedge means in forcing the sections of said split die tightly together along the line of split.

6. In combination with a press having a bed and a ram, means associated with said bed forming a well thereon; a die holder associated with said ram; a split die slidably mounted in said die holder; movable wedge means mounted in said die holder; means anchored exteriorly of said die holder and extending into operative relation with said movable wedges; punch means having punch portions operable within the recesses of said split die and having wedge-shaped head portions protruding from said split die; said wedge-shaped head portions having fluid flow passages opening at the tops thereof and extending therethrough to open at the punch portions thereof; means associated with said split die for sealing the openings of said fluid flow passages at the tops of said wedge-shaped head portions of the punches; and guideways arranged in said well for cooperation with said wedge-shaped head portions of the punch means, during the pressure stroke of the ram, in the accomplishing of a forming operation within the recesses of the said split die; said means anchored exteriorly of the die holder being effective, during the pressure stroke of the ram, to actuate said movable wedge means in forcing the sections of said split die tightly together along the line of split.

7. In combination with a press having a bed and a ram, means associated with said bed and forming a well thereon; a die holder associated with said ram; a split die slidably mounted in said die holder; movable wedge means mounted in said die holder; means anchored exteriorly of said die holder and extending into operative relation with said movable wedge means; punch means having punch portions operable within the recesses of said split die and having wedge-shaped head portions protruding from said split die; guideways arranged in said well for cooperation with said wedge-shaped head portions of

the punch means, during the pressure stroke of the ram, in the accomplishing of a forming operation within the recesses of the said split die; said means anchored exteriorly of the die holder being effective, during the pressure stroke of the ram, to actuate said wedge means in forcing the sections of said split die tightly together along the line of split; platform means aligned with the portion of said die holder which slidably receives said split die; means associated with said platform means for retaining one section of said split die stationary; and movable means associated with said platform means for engaging the other section of said split die and moving it relative to the first named section of the split die. 10 15

8. In combination with a press having a bed and a ram, means associated with said ram and forming a well thereon; a die holder articulately suspended from said ram, said die holder comprising upper and lower bridge members forming a receiving passage therebetween; stationary wedge means mounted adjacent opposite ends of said receiving passage; movable wedge blocks cooperatively mounted, with respect to said stationary wedge means, next adjacent thereof inwardly of the said passage, said movable wedge blocks having slideway surfaces which define the lateral limits of a receiving passage for a split die; a split die mounted in said receiving passage of said die holder; means anchored exteriorly of said die holder and extending into operative relation with said movable wedge blocks; punch means having punch portions operable within the recesses of said split die and having wedge-shaped head portions protruding from said split die; and guideways arranged in said well for cooperation with said wedge-shaped head portions of the punch means, during the pressure stroke of the ram, in the accomplishing of a forming operation within the recesses of the said split die; said means anchored exteriorly of the die holder being effective, during the pressure stroke of the ram, to actuate said wedge means in forcing the sections of said split die tightly together along the line of split thereof. 40 45

EDWARD S. CORNELL, JR.
